J. T. McCABE.

DOOR HANGER.

APPLICATION FILED OCT. 27, 1909.

1,038,502.

Patented Sept. 10, 1912.

WITNESSES:

John J. Meyer

John T. McCabe

INVENTOR.

UNITED STATES PATENT OFFICE.

JAMES T. McCABE, OF NEW YORK, N. Y.

DOOR-HANGER.

1,038,502.

Specification of Letters Patent. Patented Sept. 10, 1912.

Application filed October 27, 1909. Serial No. 524,995.

To all whom it may concern:

Be it known that I, JAMES T. McCABE, a citizen of the United States of America, and a resident of the borough of Manhattan, city, county, and State of New York, have invented certain new and useful Improvements in Door-Hangers, of which the following is a specification.

My invention relates to a combined door hanger and track, the upper face of the track being provided with a grooved runway adapted to receive anti-friction bearing balls, while the hanger comprises in its construction, a yoke adapted to be secured 10 to a door and to a rider bar provided on its lower edge or face, with a grooved runway adapted to seat and move on the anti-friction balls located in the runway of the track, said balls being held in spaced relation to each other by means of a vertically disposed spacer.

For this purpose it consists in the combination and arrangement of the several parts of which it is composed as will be 20 hereinafter more fully described and claimed.

Referring to the accompanying drawings in which corresponding parts are designated by corresponding marks of reference: 30 Figure 1 is an elevation of a door hanger constructed in accordance with this invention. Fig. 2 is an end view showing the supporting bracket of the stationary track. Fig. 3 is a vertical section on lines 3—3 35 of Fig. 1. Fig. 4 is a fragmental top plan view of the spacing plate of the balls. Fig. 5 is a side elevation thereof. Fig. 6 is an end elevation of a modified form of the invention, showing a slightly different type 40 of track and rider bar and their supporting devices. Fig. 7 is a sectional view taken through a modified form of stationary track.

The stationary track A is carried above 45 the door opening by suitable brackets B, one located at each end thereof, only one of these brackets being shown in the drawing. It will be understood that the stationary track A extends sufficiently to the side 50 of the door opening to permit the door to be opened. The door C is carried by the yokes D (only one shown) from the rider bar E located above the stationary track. The track has a runway a in the upper face

thereof extending from end to end, and has 55 a longitudinal slot a' in the base of such runway, while the rider bar E has a corresponding runway e and slot e' in its lower face. A series of balls F are mounted within the runways a and e of the stationary 60 track A and rider bar E, the balls serving as means whereby the movable rider-bar is carried upon the track and is allowed to run thereon with the minimum of frictional resistance. 65

In order to properly space the balls F and prevent their approaching each other too closely or gathering at any part of the runways they are contained within apertures g of a spacing plate G. This plate in 70 the assemblage of the hanger is placed in a vertical plane, its lower edge being contained within and guided by the slot a' in the track while its upper edge is contained in and guided by the slot e' in the rider bar. This plate therefore serves to 75 separate the balls, and is entirely contained, concealed and protected against injury or rusting. The balls are held within the apertures of the plate by ears g' struck up 80 from the side of the plate in the process of forming the apertures g, a part of the metal of the plate on each side of the apertures being bent up to each side of the plate and being partly closed after the insertion of 85 the balls to hold the latter, as is fully shown in Figs. 4 and 5.

In Fig. 6 I have shown a track A' and a rider-bar E' slightly different in construction, whereas in the preceding figures these parts are represented as substantially rectangular cross bars. I here show them as formed of roller sheet metal shaped to form the runways a and e, and the slots a' e', as before but in lieu of the end brackets B the 90 stationary track is provided at the side with a vertical web B' which at its top is bent back horizontally to form a cover B² provided with a depending flange B³. The cover B² may be secured at proper intervals 95 above the door opening in the usual manner. In a like manner the rider-bar has a depending web D' on its one side, which at its bottom is bent forwardly and horizontally to afford a base D² provided with a strengthening flange D³. The door may be hung from the base in the usual manner. 100 105

In Fig. 7 I have illustrated still another

manner of forming a run-way, be it either movable or stationary, which can be used in lieu of those shown in Figs. 1, 2 and 3, by a proper shaping of the hangers and 5 brackets. As here shown a sheet of metal of the proper length and width is folded or bent longitudinally on itself as at K to form a web K', the ends of the metal are flared or separated from each other as at 10 K² to form flanges. To strengthen these flanges I place thereon a V-shaped reinforcing strip K⁴ and roll the edges of the sheet metal forming the base K³ of the flanges thereover as at K⁵, thus affording a 15 cheap and simple construction which possesses much strength. I wish to call attention to the fact that the apex of the triangle formed by the inclined flanges in this type of my invention forms the runway to receive the edge of the spacing plate.

It will be understood that as a result of this construction, I have provided a door hanger possessing but few parts, all of which may be easily formed by the usual 20 mechanical processes and which may be readily assembled by unskilled labor and one that when they are assembled is not liable to become disengaged.

What I claim is:—

1. In a door hanger, the combination of 30 a stationary track having a grooved upper face and a longitudinal slot in the base of such groove, of a rider bar having a grooved face and a longitudinal slot in the base of such groove, balls contained within the 35 grooves in the track and rider bar, and a flat ball retaining spacing plate, having its upper and lower edges contained in the slots in the track and rider bar respectively, the plate having ears struck up thereon from 40 its opposite sides to serve as ball retainers.

2. In a door hanger, a track composed of a strip of metal bent longitudinally upon itself to form a web of double thickness, the tops of the metal comprising the web being 45 bent outwardly to form inclined flanges, a V-shaped reinforcing flange member laid on the flange thus formed and secured by the inturned edges of the flange member, whereby a longitudinal groove is provided in the 50 base of the track in the flange and between the inturned edges.

JAMES T. McCABE.
